US00D626539S

(12) **United States Design Patent**
Brown et al.

(10) **Patent No.:** **US D626,539 S**
(45) **Date of Patent:** ** *Nov. 2, 2010

(54) **PORTABLE ELECTRONIC DEVICE CASE**

(75) Inventors: **Dustin Brown**, Chicago, IL (US); **Scott Wilson**, Chicago, IL (US); **Jon Godston**, Chicago, IL (US); **Daniel Berg**, Antioch, IL (US)

(73) Assignee: **Uncommon LLC**, Chicago, IL (US)

(*) Notice: This patent is subject to a terminal disclaimer.

(**) Term: **14 Years**

(21) Appl. No.: **29/341,734**

(22) Filed: **Aug. 11, 2009**

(51) **LOC (9) Cl.** **14-03**

(52) **U.S. Cl.** **D14/250**

(57) **CLAIM**

The ornamental design for a portable electronic device case, as shown and described.

DESCRIPTION

FIG. 1 is a perspective front view of a portable electronic device case, wherein the upper and lower case portions are assembled together;

FIG. 2 is a front elevation view thereof;

FIG. 3 is a back elevation view thereof;

FIG. 4 is a left side elevation view thereof;

FIG. 5 is a right elevation view thereof;

FIG. 6 is a top plan view thereof;

FIG. 7 is a bottom plan view thereof;

FIG. 8 is a front elevation view of the portable electronic device case, wherein upper and lower case portions are shown separated for ease of illustration; and,

FIG. 9 is a left side elevation view thereof.

In the drawing, the broken lines depict unclaimed environment.
